FREDERICK K. VREELAND, OF MONTCLAIR, NEW JERSEY, ASSIGNOR TO VREELAND APPARATUS COMPANY, INC., OF NEW YORK, N. Y., A CORPORATION OF NEW YORK.

MULTIPLEX TELEGRAPHY.

1,171,814.

Specification of Letters Patent.

Patented Feb. 15, 1916.

Application filed June 4, 1913. Serial No. 771,669.

To all whom it may concern:

Be it known that I, FREDERICK K. VREELAND, a citizen of the United States, residing at Montclair, in the county of Essex and 5 State of New Jersey, have invented a certain new and useful Improvement in Multiplex Telegraphy, of which the following is a specification.

This invention relates to the system of 10 multiplex telegraphy described in my applications, Serial No. 497194, filed May 20, 1909 and Serial No. 536963, filed January 8, 1910, wherein a number of alternating currents of different frequencies are simultaneously 15 impressed upon a common line and selectively received by a number of receiving units, each tuned to respond to one of the transmitted frequencies; and its object is to further simplify and perfect that system.

20 In the drawing, Figure 1 illustrates in diagram a system of multiplex telegraphy embodying my invention and Fig. 2 is a view in section of a form of transformer suitable for use in the system.

25 In Fig. 1 is represented a line having a plurality of sending and receiving sets at each end, sets 1, 2 and 3 being located at one end of the line, and sets 4, 5 and 6 at the other end of the line. Sets 1, 2, 5 and 6 are 30 represented diagrammatically, for the sake of simplicity, by their sifting circuits alone. In sets 3 and 4 I have illustrated, with greater detail, one form of a combined sending and receiving set, which may be regarded as typical of the various alternative 35 forms of the apparatus described in my former applications.

In my application Serial No. 497194, I have described, as one of the important features of the invention, a plurality of tuned 40 sifting circuits, shunted across or connected in parallel relation to the line, each sifting circuit having a large unbalanced reactance relative to the line impedance, at the nearest foreign frequency. In that application, I have shown the sifting circuits connected in parallel relation to the line by a direct metallic connection.

In my application, Serial No. 536963, I 50 have shown a modification in which a sifting circuit is shunted across the line, not by a direct metallic connection, but through a transformer of unequal windings, which permits the large unbalanced reactance relative to the line impedance to be secured 55 without the use of such large individual in-

ductance and capacity reactances as are required when a direct metallic connection is used.

In the present invention, still greater simplicity and effectiveness are secured by using a single transformer of unequal windings for connecting, in parallel relation to the line, a plurality of sifting circuits, with their associated sending and receiving apparatus.

In Fig. 1, a line is shown having at each end a transformer of unequal windings, P, S. The high voltage winding of each transformer is connected to the line, and the low voltage winding of each is connected to a local or auxiliary line A, B, A', B'. Across these local or auxiliary lines, the various sending and receiving sets are connected in parallel.

In the two sets, 3 and 4, which are shown in greater detail, there are bifurcated sifting circuits comprising the main inductance L₃, the capacity C₃ and the double contact key K, which makes contact through the contact a with the sending branch, including the secondary coil S₃, whereby power is drawn from the oscillator O, and the primary coil P_{3a}, whereby the transmitted signals are communicated to the receiver. The key also makes alternative contact through the contact b, with the receiving branch containing the primary coil P_{3b}, whereby received signals are communicated to the receiver. Both coils P_{3a} and P_{3b} are in inductive relation with the coil S₄, which operates also as the inductance of the tuned receiving circuit S₄R, including the electrostatic receiver R, which operates also as the capacity whereby the circuit is tuned. The sifting circuit L₃ C₃ K of set 3, and the sifting circuits of sets 1 and 2, are connected in parallel relation to the auxiliary line A, B, and also, through the transformer S P, to the main line. In like manner, the sifting circuits of sets 4, 5 and 6 are connected in parallel relation to the line at its distant end.

The inequality of the windings P S of the transformers, not only makes the potential differences across the auxiliary lines A, B, A', B' smaller than those across the main line, but it has the further effect of multiplying all the reactances of its associated circuits with respect to the main line, so that the requisite large unbalanced reactance for foreign frequencies, relative to the

line impedance, may be secured with relatively small absolute values of the inductance and capacity reactances. In this way, I eliminate altogether the tendency to large 5 voltages across the inductance coils and the condensers, which in my first application (and in part in my second application) is avoided by subdividing the capacity and inductance units, and I simplify and reduce 10 the cost of the apparatus by reducing the number of turns of wire in the coils and by avoiding a multiplicity of transformers.

The transformer P, S differs from the other transformers in the system in an important 15 particular. The transformer $P_{3a}S_4$ or $P_{3b}S_4$, for example, is a transformer of unequal windings, and in the case of the coil P_{3b} , the coupling with the secondary S_4 is much closer than that of the coil P_{3a} with 20 S_4 . In either case, however, the coupling is essentially a loose one, so that the tuned resonant circuit S_4R may oscillate freely, and thus secure its full measure of selectivity. The function of the transformer P, S, however, 25 is quite different. In this case, freedom of selective resonance is not required; but rather, a rigid connection of the auxiliary line A B or A' B', with the main line, so that the oscillations transmitted are 30 forced oscillations, and the auxiliary line becomes, in effect, an extension of the main line, on which, however, voltages, reactances, etc., are changed by a multiplying factor, depending upon the ratio of transformation 35 of the transformer P, S. To this end, the transformer P, S should be closely coupled. I prefer to use a transformer having a core of very fine iron wires severally insulated with enamel, as illustrated in Fig. 2, 40 in which the core is shown by D and the high and low voltage windings by P, S.

Close coupling is further important, inasmuch as the high voltage circuit is not tuned, and the reactance of the winding P 45 would tend to reflect the incoming signals and prevent them from passing through it, if it were not for the effect of the secondary coil and its associated circuits. The secondary, however, by virtue of the large mutual 50 induction of a closely coupled transformer, has the effect of neutralizing the self-induction of the primary P, at any frequency for which there is a sifting circuit in which the reactances have been balanced by tuning to 55 that frequency. Currents of any frequency for which there is a sifting circuit will, therefore, pass freely through the transformer P, S in either direction, and the working of the auxiliary lines A B and A' 60 B' will be equivalent to that of the main line, except as it is modified by the ratio of transformation of the transformer. The main line with its simple aperiodic high

voltage winding becomes, in effect, a part of the complex tuned low voltage system, 65 whose parts, including the transformer windings, are proportioned with reference to the line constants to secure the requisite selectivity. Any of the forms of apparatus which, in my former applications, I have 70 shown connected to the line by a direct metallic connection, can be used with similar effect in the present arrangement, the inductance, capacity, and other reactances of the sifting circuit being so chosen as to have 75 the requisite value with respect to the line when multiplied by the square of the ratio of transformation of the transformer.

What I claim is:—

1. In a system of multiplex telegraphy by 80 alternating currents of different frequencies, the combination with a line, of a transformer having a simple aperiodic high voltage winding connected to the line and a low voltage winding forming part of a complex 85 tuned low voltage system whereby the self-induction of the transformer is neutralized at a plurality of definite frequencies, substantially as set forth.

2. In a system of multiplex telegraphy by 90 alternating currents of different frequencies, the combination with a line, of a transformer of unequal windings having its high voltage winding connected to the line and a plurality of tuned sifting circuits connected in parallel to the low voltage winding of the transformer, said transformer being adapted to pass simultaneously and without reflection the currents transmitted and received by the several sifting circuits and 100 transmitting and receiving means associated with the sifting circuits, substantially as set forth.

3. In a system of multiplex telegraphy by 105 alternating currents of different frequencies, the combination with a line, of a transformer of unequal windings having its high voltage winding connected to the line and a plurality of tuned sifting circuits connected in parallel to the low voltage winding of the transformer and having when thus connected a large unbalanced reactance for 110 small frequency differences relative to the equivalent line impedance, said transformer being adapted to pass simultaneously and 115 without reflection the currents transmitted and received by the several sifting circuits and transmitting and receiving means associated with the sifting circuits, substantially as set forth.

This specification signed and witnessed this second day of June, 1913.
